APPAREL CLASP

William J. Bissell, Pasadena, Calif.

Application May 17, 1935, Serial No. 21,970

9 Claims. (Cl. 24—248)

This invention relates to improvements in a garment clasp.

The general object of this invention is to provide an improved garment clasp which securely 5 grips portions of a garment without tearing or marring them.

A further object of my invention is to provide a garment clasp which is so constructed that a garment may be readily engaged and disengaged.

10 Other objects and the advantages of this invention will be apparent from the following description taken in connection with accompanying drawing, wherein

Fig. 1 is a front view of my improved garment 15 clasp;

Fig. 2 is a rear view of the garment clasp shown in Fig. 1;

Fig. 3 is an enlarged section taken on line 3—3 of Fig. 1;

20 Fig. 4 is a view similar to Fig. 3 showing the clasp in an open position;

Fig. 5 is an enlarged fragmentary perspective detail of a portion of the clasp shown in Fig. 1;

Fig. 6 is a front view of a modified form of my 25 invention;

Fig. 7 is a section taken on line 7—7 of Fig. 6;

Fig. 8 is a section taken on line 8—8 of Fig. 6;

Fig. 9 is a front view of a further modification of my invention, and

30 Fig. 10 is a section taken on line 10—10 of Fig. 9.

Referring to the drawing by reference characters I have indicated my improved garment clasp generally at 10. As shown the garment clasp 10 is preferably made of metal although other suitable material may be employed. It comprises a body portion 12 having two gripping members 13 and 14 depending therefrom. The body 12 is shown as made of a piece of flat metal and adjacent the top thereof includes two spaced transverse apertures 15 and 16 which form a bar portion 16' therebetween. Adjacent its lower end and adjacent each side thereof the body material is curved forward upon itself to form two spaced bearing portions 17. Intermediate the bearing portions 17 and a predetermined distance thereabove the body material is curved backward upon itself to form a bearing portion 18. Furthermore the axis of the bearing 18 is spaced a predetermined distance in the rear of the axis of the bearing portions 17.

The gripping member 13 is made of flat metal material and includes a horizontal trunnion bar portion 19 which is positioned in the bearing portion 18 of the body 12. The trunnion bar 19 has

adjacent each end thereof a depending arm 20. The arms 20 are positioned outside the bearings 17 and therebelow converge to a head member 21. The head 21 is of greater width than the combined width of the arms 20 where they merge 5 into the head and the head includes a top bar 22 having a front lip 23 depending therefrom. Adjacent the juncture of the lip 23 and the bar 22 and extending inwardly from each end of the lip the head is preferably slotted as at 23' to provide 10 resiliency for the lip.

Below the lip 23 the head includes a foot portion 24 connected to the bar 22 by spaced offset bar portions 25. The forward edge of the lip 23 overhangs the rear edge of the foot 24 as clearly 15 shown in the drawing. Beneath the lip and between the lip 23 and the foot 24 and between the bars 25 a rectangular space 26 is formed. (See Figs. 4 and 5.) The lower edge of the foot portion 24 is shown as curved but may be of any desired shape. 20

The gripping member 14 is made of flat metal material and includes a horizontal trunnion bar portion 27 which is positioned in the bearing portions 17 of the body 12. The trunnion bar 27 has adjacent each end thereof a depending arm 28 which like the arms 20 of the gripping member 13 converge downward to a head member 29. The head member 29 is of greater width than the combined widths of the arms 28 where they merge into the head but is of less width than the space between the side bars 25 of the head 21. The lower edge of the head 29 depends below the lower edge of the lip 23 of the head 21 but is spaced above the lower edge of the foot portion 24. The lower edge of the head 29 is preferably 35 curved to substantially match the curvature of the lower edge of the foot portion 24 of the head 21.

The arms 20 of the gripping member 13 are 40 curved forward from the trunnion bar 19 as indicated at 39 to pass forward of the trunnion bar 27 so that they will be disposed close to the arms 28 of the gripping member 14.

The relative positions of the trunnion bars 19 and 27 are such that when the gripping member 13 is swung upwards to approximately right angles to the body 12 as shown in Fig. 4 and the gripping member 14 is moved to a similar position as indicated by the dotted lines in Fig. 4 the lower end of the head 29 of the gripping member 14 can pass the upper end of the foot portion 24 of the gripping member 13 and then when both gripping members are swung downward together 50 55

the head 29 of the member 14 enters the space 26 of the head 21. (See Figs. 3 and 5.)

For attaching the garment clasp 10 to a garment I may provide a flexible band 31 which may be made of elastic or non-elastic material. The reach 32 of the band 31 is secured to the garment or article to which the garment clasp 10 is to be attached and extends downward over the front face of the body 12 thence through the aperture 15 and over the rear face of the bar 16' and then through the aperture 16 thence downward under the bearing portions 17, then upward and over the rear face of the bearing portion 18 and thence upward and through the aperture 15 to a position 15 between the front face of the body and the rear face of the front reach 32 of the band.

When it is desired to grip a flexible article such as a stocking as indicated at 33 with the device 10 and assuming the device to be in an open position, 20 the gripping member 13 is swung upward as previously described and shown in Fig. 4.

The material 33 is then placed against the front face of the gripping member 14 and the gripping member 14 swung upward until the material 33 engages the back face of the lip 23 as indicated by the dotted lines in Fig. 4. Whereafter both gripping members are swung downward together whereupon the head 29 of the gripping member 14 enters the face 26 of the head 21 and carries the material 33 thereinto with it. The gripping members are continued to be swung downward until they reach the position shown in Fig. 3 wherein the head 29 of the member 14 is positioned to the rear of its trunnion bar 27 and further rearward movement of the members is restricted by the engagement of a portion of the member 13 with the trunnion bar 27.

This positioning of the head 29 at the rear of its trunnion forms a locking means to prevent 40 accidental opening of the garment clasp. In this position the material 33 is firmly pressed between the front face of the head 29 and the rear face of the lip 23 and between the rear face of the lip 23 and the front face of the foot 24 thus firmly 45 securing the material 33 to the garment clasp 10. The spring of the lip 23 which projects beyond the foot 24 serves to hold the head 29 in firm gripping engagement. The resilience provided for the lip 23 by the slots 23' allows the lip 23 to spring slightly to accommodate various thicknesses of material. When strain is applied to the reach 32 of the band 31 it tends to swing the lower end of the body 12 forward thereby tending to put a forward and downward strain on the member 14 which tends to force the head 29 further into the space 26 of the head 21 thereby more firmly gripping the material 33.

In Figs. 6, 7, and 8 I have indicated a modified form of my invention generally at 35. As shown 60 the garment clasp 35 comprises a body portion 36 having two gripping members 37 and 38 depending therefrom. The body 36 is made of a piece of flat metal and adjacent the top thereof includes two spaced transverse apertures 39 and 40 which form a bar portion 41 therebetween. Adjacent its lower end the body material is rounded over to form a bearing portion 42. A predetermined distance above the bearing 42 and adjacent each side thereof the body material is 65 slit and outstruck to form bearing portions 43. Furthermore the axis of the bearing portions 43 is spaced a predetermined distance in the rear of the axis of the bearing 42.

The gripping member 37 is preferably made of 75 a single length of round material and adjacent

its lower end includes a horizontal reach 44 which intermediate its length is offset as at 45 to form a pocket as indicated at 46. (See Fig. 8.) From each side of the horizontal reach 44 the wire is bent vertical as at 47, then convergently upward as at 48, thence outwardly as at 49 to beyond the sides of the bearing 42 and then it is curved upward and inwardly to form a pair of horizontal trunnion portions 50 which are positioned in the bearing portion 42.

The gripping member 38 like the gripping member 37 is made of a single length of material and adjacent its lower end includes a horizontal reach 51 which forms a finger portion of a length to fit within the pocket 46 of the gripping arm 36. 15 From each side of the horizontal portion 51 the wire is curved downwardly and then upwardly as at 52 into vertical sections 53. The wire is then bent convergently upward as at 54 and thence divergently upward as at 55 to a location beyond 20 the outsides of the bearing portions 43 where each arm 55 is bent to a horizontal position to form a trunnion member 56. The trunnions 56 are positioned in the bearing portions 43 of the body 36. The arms 55 of the gripping member 38 are 25 curved forward from the trunnion portions 56 as indicated at 57 to pass forward of the bearing 42 and over the gripping member 36.

The relative locations of the trunnion portions 50 and 56 of the gripping members is such that 30 when the gripping members are swung forwardly and upwardly a predetermined distance the finger portion 51 of the member 38 moves outward from the pocket portion of the member 37 and thereafter can be swung above the member 37 as indicated by the dotted lines in Fig. 7. When the member 38 is swung downward from the position indicated by the dotted lines it engages the member 37 and swings it downward with it. As the two members 37 and 38 continue to swing downward 40 the finger portion 51 of the member 38 enters the pocket portion 45 of the member 37.

For attaching the garment clasp 35 to a garment I provide a flexible band 57 which may be made of elastic or nonelastic material. The reach 45 58 of the band 57 is secured to the garment or article to which it is desired to attach the garment clasp 35 and extends downward over the front face of the body 36, thence through the aperture 39 and over the rear face of the bar 41 50 and then through the aperture 41 thence downward under the bearing 42, then upward and over the rear face of the body and through the aperture 39 to a position between the front face of the body and the rear face of the front reach 55 58 of the band.

When it is desired to grip a flexible article 59 such as a stocking with the device 35 and assuming the device 35 to be in an open position, the gripping member 38 is swung upward as 60 previously described and shown in Fig. 7. The material 59 is then placed over the finger 51 of the member 37 as indicated by the dotted lines in 65 7. The member 38 is then moved downward into engagement with the member 37 and thereafter both are moved downward to the position shown in full in Fig. 7. As the finger 51 enters the pocket 46 the cloth 59 is carried thereinto with it and is firmly clamped between the front face of the finger 51 and the rear face of the 70 pocket bar portion 45.

In Figs. 9 and 10 I have indicated a further slightly modified form of my invention generally at 60. As shown the device 60 includes a body member 61 and a finger member 62. The finger 75

member 62 is made of a piece of flat material and adjacent the top thereof has a transverse aperture 63 therein and below the aperture 63 has an aperture 64 therein of less width than the aperture 63. Adjacent the lower edge of the aperture 64 the finger member includes an offset bar member 65 which extends forward of the front face of the finger member and overhangs the aperture 64 and is of less width than the aperture 64.

10 A flexible band 66 which may be elastic or non-elastic material is laid on the front face of the finger member 62 and positioned in the aperture 63 and then run back upon itself and sewed to form a loop. The portion of the band 66 above the garment clasp 60 is suitably secured to a garment or other article to which the garment clasp is to be secured.

15 The body member 61 is made of a piece of flat metal material and adjacent the top thereof and extending from each side thereof includes arm members 67 which are bent rearward and around the band 66. The body 61 extends downward from the arms 67 and adjacent the lower end thereof has an aperture 68 therein and a bar portion 69 below the aperture. The sides of the body adjacent the lower end thereof are bent rearward to position the bar 69 in the rear of the front face of the body. At the upper edge of the aperture 68 the material of the body 61 is curved rearwardly and downwardly as indicated at 70.

20 The finger member 62 adjacent the lower end thereof includes a depending lip portion 71 which is of slightly less width than that of the body aperture 68 and extends downward to a position below the upper edge of the body bar 69.

25 When it is desired to grip a flexible article, such as a piece of cloth as indicated at 72, with the device 60 the finger member 62 thereof is moved rearwardly from the body 61 as indicated by the broken lines in Fig. 10 and the cloth 72 placed against the front face of the finger member and over the bar member 65 thereon. The finger lip 71 is then positioned in the body aperture 68 and the finger member moved downward and forward until the finger bar 65 passes through the aperture 68. The strain between the cloth 72 and the band 66 then moves the finger bar 65 towards the curved portion 70 of the body thereby firmly clamping the cloth between the finger bar 65 and the curved portion 70 of the body.

30 From the foregoing description it will be apparent that I have provided a novel garment clasp which is simple in construction and highly efficient in use.

35 I claim:

1. A garment clasp comprising a body member having a pair of gripping members pivoted thereon, one of said gripping members including a head portion having an aperture therein and including a foot portion below said aperture, said head portion including a lip portion extending downwardly to a position above the top edge 40 of said foot portion, said other gripping member including a head portion, when both of said gripping members are pendant said head portion of said second gripping member being adapted to be positioned in said aperture of said first gripping member and to overlay said foot portion thereof.

45 2. A garment clasp comprising a body member having two gripping members pivoted thereto, coacting means on said members to engage an article, said body having a pair of elongated

5 apertures therein adjacent the upper edge thereof, said apertures forming a rib portion therebetween, a band of flexible material, said band extending downward over the front face of said body and being positioned in said body apertures and engaging the rear face of said rib member therebetween, said band continuing downward over the front face of said body and being positioned in said apertures of said gripping members and under said first bearing portions and then extending upward over the rear face of said body and being positioned in the uppermost of said body apertures and continuing upward between the front face of said body and the rear face of the front reach of said band.

10 3. A garment clasp comprising a body member having a pair of gripping members depending therefrom, said body having bearing portions thereon adjacent its lower end and a second bearing portion thereabove, the axes of said 15 bearing portions being offset one from the other, one of said gripping members including a trunnion portion positioned in said second bearing, said one gripping member including a head portion having an aperture therein and including a 20 foot portion below said aperture, said head portion including a lip portion extending downward to a position above the top edge of said foot portion, said other of said gripping members including a trunnion portion positioned in said 25 first bearing, said other gripping member including a head portion, when both of said gripping members are pendant said head portion of said second gripping member is adapted to be positioned in said aperture of said first gripping 30 member and to overlay said foot portion thereof.

4. A garment clasp comprising a body member having two gripping members depending therefrom, said body adjacent its lower end including bearing portions, said body having a 40 second bearing portion thereon positioned above said first bearing portion, the axis of said second bearing portion being positioned at one side of the axis of said first bearing portions, one of said gripping members including a horizontal trunnion portion positioned in said second bearing, said one gripping member having arms converging downwardly to an enlarged head portion, said head portion including an upper horizontal bar portion and a horizontal foot portion spaced below said bar portion and at the rear of said bar portion, said head portion including side bars connecting said top bar portion and said foot portion, the lower edge of said top bar portion, the top edge of said foot portion 45 and the inner edges of said side bar portions defining a pocket, said head including a lip portion depending from said top bar portion and being of less width than said pocket and the lower edge of said lip portion overhanging the top edge 50 of said foot portion, the other of said gripping members including a horizontal trunnion portion positioned in said first bearing portion, said other gripping member converging downward to an enlarged head portion which is of less 55 width than said pocket, said first gripping member extending over the front face of said second gripping member, the lower edge of said other gripping member head depending below the upper edge of said first gripping member foot portion when both of said gripping members are 60 in a pendant position.

5. A garment clasp comprising a body member having two gripping members pivoted thereon, the axes of said pivots being offset, one of 65

70

75

said gripping members converging downwardly to an enlarged head portion, said head portion including an upper horizontal bar portion and a horizontal foot portion spaced below 5 said bar portion and at the rear of said bar portion, said head including side bar portions connecting said top bar portion and said foot portion, the lower edge of said top bar portion, the top edge of said foot portion and the 10 inner edges of said side bar portions defining a pocket, said head including a lip portion depending from said top bar and being of less width than said pocket and the lower edge of said lip overhanging the top edge of said foot portion, 15 the other of said gripping members converging downwardly to an enlarged head portion which is of less width than said pocket, said first gripping member extending over the front face of said second gripping member, the lower edge of 20 said second gripping member head depending below the upper edge of said first gripping member foot portion when both of said gripping members are in a pendant position.

6. A garment clasp comprising a body member 25 having two gripping members pivoted thereon, said body member having a pair of transverse elongated apertures therein adjacent the upper edge thereof, said apertures forming a rib portion therebetween, one of said gripping members including arms converging downwardly to an enlarged head portion, said one gripping member having an aperture therein above said head portion, said head portion including a top bar portion and a foot portion spaced below said 30 top bar and at the rear of said bar, said head portion including side bars connecting said top bar and said foot portion, the lower edge of said top bar, the top edge of said foot portion and the inner edges of said side bars defining a pocket, said head portion including a lip portion depending from said top bar and being of less width than said pocket and the lower edge of said lip portion overhanging the top edge of said foot portion, the other of said gripping members including arms converging downward to an 35 enlarged head portion, said other gripping member having an aperture therein above the head thereof, said last mentioned head being of less width than said pocket, said other gripping member overlaying the front face of said one gripping member, when both of said gripping arms are in a pendant position the lower edge of said other gripping member depending below the upper edge of said first gripping member foot portion, a band of flexible material, said band extending downward over the front face of said body and being positioned in said body apertures and engaging the rear face of said rib member therebetween, said band continuing downward 40 over the front face of said body and being positioned in said apertures of said arms and under said first bearing portions and then extending upward over the rear face of said body and being positioned in the uppermost of said body apertures and continuing upward between the front face of said body and the rear face of the front reach of said band.

7. A garment clasp comprising a body member having two gripping members pivoted thereto, said body having a pair of superimposed elongated apertures therein adjacent the upper edge thereof, said apertures forming a rib portion 5 therebetween, each of said gripping members being made of wire and one of said gripping members being bent downwardly from each side of said body then inwardly thence outwardly and then downwardly to a horizontal portion, said horizontal portion intermediate its width being bent forward to form a horizontal pocket portion, the wire of said other gripping member being bent downwardly from each side of said body and converging, then inclined outward, thence downward 10 to a horizontal portion, said horizontal portion of said other gripping member intermediate its width including an upwardly extending finger portion of a length to fit within said pocket portion of said first gripping member and the sides of 15 said finger portion being adapted to engage the sides of said pocket portion.

8. A garment clasp comprising a body member having two gripping members depending therefrom, said body adjacent its lower end including 25 a bearing portion and having thereabove a second bearing portion, the axis of said second bearing portion being offset from the axis of said first bearing portion, each of said gripping members being made of wire, one of said gripping members 30 including a trunnion portion positioned in said first bearing, the wire of said one gripping member being bent downwardly from said trunnion on each side of said body then inwardly thence outwardly and then downwardly to a horizontal portion, said horizontal portion intermediate its width being bent forward to form a horizontal pocket portion, said other of said gripping members including a trunnion portion positioned in 35 said second bearing, the wire of said other gripping member being bent downwardly from each side of said body and converging, then inclined outward, thence downward to a horizontal portion, said horizontal portion of said other gripping member intermediate its width including an upwardly extending finger portion of a length to fit 40 within said pocket portion of said first gripping member and the sides of said finger portion being adapted to engage the sides of said pocket portion, the top of said finger portion being approximately 45 above or on the same plane as the top of said pocket portion when both of said gripping members are pendant.

9. A garment clasp comprising a body member having a pair of gripping members pivoted thereon, one of said gripping members including a head portion having a transverse top bar thereon and having a transversely extending foot portion spaced from said bar to form a transverse aperture, said other gripping member including a head 55 portion, said head portion being of a length to fit in said aperture, when both of said arms are pendant said head portion of said second gripping member being adapted to be positioned in said aperture of said first gripping member and to be 60 disposed beneath said top bar.

WILLIAM J. BISSELL.
